ROBERT M. KERR, OF DETROIT, MICHIGAN, ASSIGNOR TO DETROIT DENTAL MANUFACTURING COMPANY, OF DETROIT, MICHIGAN, A CORPORATION OF MICHIGAN

MIXING BOWL

Application filed March 25, 1929. Serial No. 349,841.

The invention relates to mixing bowls of that type used by dentists in the mixing of plastic compounds and the invention consists in the novel construction as hereinafter set forth.

In the drawings:

Figure 1 is a plan view;

Figure 2 is a vertical central cross section on line 2—2 of Figure 1.

10 In the present state of the art mixing bowls of the use above described have been constructed, the bowl proper being formed of flexible rubber and having a rigid cap on which is mounted mechanism for operating the mixing blade. It is usual, however, to arrange this mechanism on a handle construction extending upward a considerable distance above the top of the bowl. My improvement consists in a construction where 15 20 25 30 35 40 45

wheel K intermeshing with the pinion H. The pivot J is preferably formed by a shoulder screw engaging a threaded aperture in the block G and having a head J' for retaining the gear wheel K. L is a crank handle secured to the gear wheel K by screws M and being provided at its free end with a swivel handle N.

With the construction as described it will be noted that the gearing is arranged within the recess in the cover formed by the flaring flange C and the crank handle L is in a plane but slightly above the upper edge of the bowl. This makes a very compact arrangement and as the center of gravity is low, there is no danger of the bowl tipping over. The construction is also one which is very convenient for operation. The operator can grasp the bowl in one hand and turn the crank handle with the other.

What I claim as my invention is:

1. In a mixing bowl comprising a flexible bowl proper having a flaring mouth, a rigid cover forming a re-enforcement for said bowl and having a flaring portion for fitting within said mouth, a mixing blade beneath said cover of a contour substantially corresponding to that of the inner wall of the bowl, a shaft on which said blade is mounted projecting upward through said cover, a crank handle eccentric to said shaft and a step-up gearing from said crank handle to said shaft arranged parallel to the plane of said cover and within the recess formed by said flaring flange.

2. A mixing bowl comprising a flexible bowl proper having a flaring mouth, a rigid cover provided with a flaring flange for fitting within said mouth terminating in a radially outwardly extending flange fitting over the upper edge of the bowl, said cover forming a re-enforcement for the bowl, a mixing blade beneath said cover and of a contour approximately corresponding to that of the inner wall of the bowl, a shaft on which said

In detail, A is the bowl of usual construction formed of flexible rubber, B is a cap or cover for the bowl which has a flaring flange C and a radially outwardly extending flange D respectively for fitting within and over the upper edge of the bowl, E is a mixer blade mounted on the under side of the cover B and of a contour corresponding substantially to that of the cross section of the bowl. This blade is attached to a rotary shaft F which extends through a bearing G formed by a plate or block on the upper side of the cover B and H is a pinion mounted on the upper end of said shaft above the bearing G. The block or bearing G is secured to the cover by riveting or other suitable securing means as indicated at I and extends laterally from one side to the flange C. J is a pivot for a gear

blade is mounted extending through said cover in the axis of said bowl, a block secured to said cover forming a bearing for said shaft, a crank handle eccentric to said shaft and a 5 step-up gearing for communicating motion from said crank handle to said shaft, said gearing being arranged parallel to said block and within the recesses formed by the flaring flange of said bowl.

10 In testimony whereof I affix my signature.
ROBERT M. KERR.
